UNITED STATES PATENT OFFICE.

GEORGE W. SPRAGINS, OF FALLS CITY, NEBRASKA.

CULTIVATOR.

No. 895,120.

Specification of Letters Patent.

Patented Aug. 4, 1908.

Application filed September 24, 1907. Serial No. 394,365.

To all whom it may concern:

Be it known that I, GEORGE W. SPRAGINS, a citizen of the United States, residing at Falls City, in the county of Richardson and 5 State of Nebraska, have invented a new and useful Cultivator, of which the following is a specification.

This invention relates to cultivators and its object is to provide a combined disk and 10 shovel device of this character designed to simultaneously operate upon two rows of listed or check rowed corn.

Heretofore it has been possible to go over the corn only about twice because after it has 15 reached a certain height it has been necessary to dispense with the low machines and to use a high cultivator in lieu thereof.

The object of the present invention, however, is to provide a machine which moves 20 close to the ground but which can nevertheless be employed for cultivating the corn during all stages.

A still further object is to improve upon the construction of devices of this character 25 such as heretofore used by simplifying the same and rendering it more easily operated and manipulated.

Another object is to provide improved means whereby either the disks or the shovels 30 at the sides of each row can be separately manipulated or simultaneously raised or lowered as may be desired.

With these and other objects in view the invention consists of certain novel features 35 of construction and combinations of parts which will be hereinafter more fully described and pointed out in the claims.

In the accompanying drawings is shown the preferred form of the invention.

40 In said drawings: Figure 1 is a plan view of the machine, the operating levers of the disks and shovels being removed. Fig. 2 is a section on line $x-x$, Fig. 1. Fig. 3 is a rear elevation of one end portion of the machine. 45 Fig. 4 is a horizontal section through a portion of the machine and showing one of the supporting wheels and its adjustable connections in plan.

50 Referring to the figures by characters of reference, A and B designate two cultivator sections and inasmuch as the two sections are similar in construction it will be necessary to describe only one of them in detail.

55 1, 1 designate the sides of the frame of each end section, said sides being preferably of trapezoidal form. The sides are rigidly

connected at the top by cross strips 2 and 3 to which is secured a tongue 4 having braces 5 extending from the sides thereof to the ends of strip 2. Arranged upon each of the 60 sides 1 are superposed guide rollers 6 and secured upon the tongue between these rollers is a guide strap 7 having a guide pin 8 extending downward therethrough and into the tongue.

65 A yoke 9 is secured to the tongue 4 at a point between the sides 1 and extends downward therefrom terminating in laterally extending feet 10 which are secured to and extend beyond the sides 1. Arranged below each of these feet is a bar 11 having a plurality of openings 12 any one or more of which is designed to receive a fastening bolt 15 extending downward through the foot and bar. A stub shaft 14 extends inwardly 70 from each bar 11 and a wheel 15 rotates thereon. An ear 16 extends forward from each bar 11 close to the stub 14 and has a rod 17 secured to it. This rod extends upward and forward and is designed to engage 75 any one of a series of openings formed in the front strip 2. By detaching the bars 11 from the feet 10 the same can be resecured in any desired position so as to hold the wheels a predetermined distance apart. It 80 will of course be necessary to readjust the rods 17 within the openings 18 so that they will extend straight forward from the ears 16 and relieve the bolts 13 from any transverse pressure caused by the forward movement of the machine.

85 Journalized within the rear portions of the sides 1 near the bottoms thereof are superposed shafts 19 and 20, the lower shaft being provided with a central arch 21 while the upper shaft 20 also has a central arch 22 which is larger than the arch 21 so that said lower arch is free to move within the upper arch. Cultivator shovels 24 are secured to the end 90 portions of the upper shaft 20 while disks 25 are preferably connected to the end portions 100 of the lower shaft. Each arch has an ear 26 extending laterally from the upper portion thereof and slidably mounted within each of these ears is a rod 27 having means such as nuts 28 for preventing the rods from being withdrawn from the ears. A spring 29 is coiled about each rod and bears at one end against one of the ears 26 while its other end contacts with a collar 30 or other suitable device upon the rod. It is therefore apparent that when the rod is pulled in one 105 110

direction motion is transmitted directly therefrom through the nut 28 to the ear 26 but when it is pushed in the opposite direction power is transmitted through the spring 5 29 to the ear 26.

Secured upon one side of the frame of the machine and extending upward therefrom is a fixed rack 31 upon opposite faces of which are pivotally mounted levers 32 and 10 33, both levers being preferably fulcrumed upon a single pin 34 extending through the rack. The lever 32 has a second rack 35 secured thereto and movable therewith while lever 33 carries a dog 36 designed to 15 engage both of the racks 32 and 35. Two rods 27 are connected to the levers 32 and 33 respectively.

The foregoing description applies equally to the two sections A and B. These sections are movably connected by a seatboard 20 37 which extends between the sets of superposed rollers 6 and under the straps 7 as shown in Fig. 1. Longitudinal slots 38 are formed within the end portions of the board 25 37 and the guide pins 8 extend through these slots and serve to limit the independent lateral movement of the sections A and B. A driver's seat 39 of the usual or any preferred form is mounted upon the middle 30 portion of board 37.

It is designed to harness two draft animals to each tongue 4 and the sections A and B may, if arranged close enough together, work two adjoining rows of corn, although it will 35 be preferable to leave one row between the sections while the two adjoining rows are being cultivated. The movable connections between the sections and the seat board allow a certain amount of independent movement of the two sections and by providing 40 the rollers 6 this movement is freely permitted. By lifting the dog 36 out of engagement with the fixed rack 31 and the movable rack 35 either of the levers 32 and 33 can be 45 swung backward or forward so as to swing either of the shafts 19 and 20 to raise or lower the cultivators carried thereby. As the rods 27 are connected to the upper portions 50 of the arches 21 and 22 considerable leverage upon the shafts is secured. Obviously as soon as either or both of the shafts has been moved to a desired position they can be locked by releasing the dog so that it will reengage the two racks.

55 By arranging the racks and dog in the manner described and shown the mechanism necessary for separately or simultaneously actuating the shafts and for locking them in any positions to which they may be moved is 60 greatly simplified.

Importance is attached to the provision of the arches 21 and 22 because by using them the machine possesses every advantage of both a low and a high cultivator. It is pos-

sible to use the machine during all stages of 65 the cultivation of corn and therefore the necessity of employing a second or high cultivator is dispensed with.

By locating the springs 29 as shown the disks or shovels are free to swing upward 70 should they strike immovable objects, said springs serving to promptly return the parts to their initial positions.

What is claimed is:

1. A cultivator of the character described 75 comprising a frame, supporting wheels adjustably connected thereto, superposed arched shafts carried by the frame, separate cultivating devices carried by the shafts, and means for independently actuating the shafts. 80

2. A cultivator of the character described comprising a frame, supporting wheels therefor, superposed arched shafts journaled within the frame, separate cultivating devices carried by the shafts, separate means for actuating the shafts, and mechanism common to said means for locking them in adjusted position. 85

3. A cultivator of the character described comprising a frame, supporting wheels therefor, superposed arched shafts journaled within the frame, the arch of one of the shafts being movable within the arch of the other shaft, separate means connected to each arch for independently swinging the arches, mechanism common to both of said means for locking the arches in adjusted position, and separate cultivating devices carried by and movable with the shafts. 90 95

4. A cultivator of the character described 100 comprising a frame, supporting wheels therefor, superposed arched shafts journaled within the frame, the arch of one of the shafts being movable within the arch of the other shaft, cushioned means connected to each arch 105 for independently swinging the arches, and separate cultivating devices carried by and movable with the shafts.

5. In a cultivator of the character described the combination with superposed 110 arched shafts and separate cultivating devices carried by the shafts; of separate means for actuating said shafts, said means comprising a fixed rack, separately movable levers journaled within each of the racks, a 115 rack movable with one of the levers, and a pawl carried by the other lever for simultaneously engaging both racks to lock the levers in fixed relation, and means for transmitting motion from the levers to the respective shafts. 120

In testimony that I claim the foregoing as my own, I have hereto affixed my signature in the presence of two witnesses.

GEORGE W. SPRAGINS.
